ELECTRIC HOIST

Guilbert M. Hunt, Willowick, Ohio, assignor to Duff-Norton Company, Pittsburgh, Pa.

Filed May 12, 1958, Ser. No. 50,852

Term of patent 14 years

(Cl. D41—1)

Figure 1 is a perspective view of an electric hoist embodying my new design, the broken line showing of the attachment hook and chain is for purpose of illustration only;

Figure 2 is a front elevational view thereof in enlarged scale, the rear being a mirror image of the front shown;

Figure 3 is a bottom plan view thereof in enlarged scale;

Figure 4 is an end view taken from the left of Figure 2; and

Figure 5 is a top plan view thereof.

I claim:

The ornamental design for an electric hoist, as shown and described.
